To all whom it may concern:

As shown by the drawing, my design is that of a number of stars set, respectively, in diamond-shaped outlines. These stars are placed upon the sheets of glass in any suitable manner. The diamond-shaped outlines are ridges

on the glass, which are also placed upon the sheets of glass in any suitable manner. 15

The configuration of the design shown in the annexed drawing when applied to sheet-glass.

In testimony whereof I have affixed my signature, in presence of two witnesses, this 22d day of July, 1887.
